UNITED STATES PATENT OFFICE.

HUBERT E. HARRIS, OF MACON, GEORGIA.

RAILWAY-RAIL-FASTENING DEVICE.

1,203,541.

Specification of Letters Patent. Patented Oct. 31, 1916.

Application filed July 18, 1916. Serial No. 109,984.

To all whom it may concern:

Be it known that I, HUBERT E. HARRIS, a citizen of the United States, residing at Macon, in the county of Bibb and State of Georgia, have invented certain new and useful Improvements in Railway-Rail-Fastening Devices; and I do hereby declare the following to be a full, clear, and exact description of the invention, such as will enable 10 others, skilled in the art to which it appertains to make and use the same, reference being had to the accompanying drawings, and to the letters and figures of reference marked thereon, which form a part of this 15 specification.

This invention relates to new and useful improvements in means for holding railway rails upon tie plates and consists in the provision of a combination tie plate and 20 spike designed to interlock and tending to securely hold the rail upon a stringer or tie.

The invention consists of a simple device of this nature having various details of construction, combinations and arrangements 25 of parts which will be hereinafter fully described, shown in the accompanying drawings and then specifically defined in the appended claims.

I illustrate my invention in the accompanying drawings, in which:—

Figure 1 is a cross sectional view through a rail and tie plate, illustrating the spike in elevation. Fig. 2 is a top plan view.

Reference now being had to the details 35 of the drawings by letter, A designates a railway rail of the usual construction having a flange B, and C is a tie or stringer supporting a tie plate D, which latter has ribs E upon the under surface thereof en- 40 gaging the upper portion of the tie, thus securely holding the plate against lateral movement. It will be noted that each plate has ribs F projecting from its upper surface and against which the opposite edges of 45 the flanges of a rail are adapted to contact. The plate is apertured as at H, H for the reception of spikes I, each of the latter pro- 50 vided with a curved wedge-shaped portion J, and each provided with inclined edge O on the rear side of the spike opposite a notch N, which latter has its inner end inclined, as shown in Fig. 1 of the drawings, said notch being adapted to receive one edge 55 of the plate and the rib E thereon, said rib having its under surface inclined at an inclination parallel to the inclined end of

the notch. The spike has a head with a laterally extending portion I' over the notch and which is adapted to engage the upper surface of the flange of a rail in the manner 60 shown clearly in the drawings.

In applying the fastening device, the plate is adjusted in place upon the tie or stringer and the ribs on the under surface thereof made to engage in the upper portion 65 of the tie, thus securely holding the tie plate from lateral movement. The rail is then placed upon the plate with the opposite edges of the flange thereof resting against the ribs F, after which the spikes 70 I are driven into the tie through the apertures in the plate D and, as the spike reaches its farthest inner limit in the tie, the wedge-shaped edge J of the spike will tend to cause the laterally extending portion I' of 75 the head to move toward the flange of the rail. This action co-operates with the action of the inclined edge of the spike against the wall of the hole in which the spike is driven to cause the latter to engage the tie plate 80 and flange in the manner shown in Fig. 1. When the spike is at its farthest inner limit in the tie, it will be noted that the edge of the flange and the inner wall of the opening through which the spike passes will contact 85 with the side wall of the notch, while the laterally extending portion of the head will engage the inclined surface of the flange of the rail, thus securely holding the latter in place. Any tendency that the spike 90 might have for any reason to loosen will be checked by the inclined end of the notch coming in contact with the inclined edge of the rib on the under surface of the plate.

It will be noted by the construction of 95 the device embodying the features of my invention that a simple and efficient means is provided for securely locking a rail and tie plate to a stringer or tie, any tendency of the spike loosening, incident to swelling 100 or shrinking of the tie or jar due to heavy trains passing over the rail, being prevented.

What I claim to be new is:—

A railway rail fastening device comprising in combination with a tie, an apertured 105 plate having ribs upon the under surface thereof adapted to engage the upper surface of the tie and having inner inclined faces, the outer edge of each rib being flush with the inner wall of an aperture, a spike having 110 a notch in the inner edge thereof and a laterally extending head for engagement

over the flange of a rail, the edge of the spike opposite said notch being beveled and the inner edge of the spike adjacent to its pointed end being beveled, the two beveled portions of the spike cooperating with the tie to cause the notched portion of the spike to engage the edge of the flange of a rail and inner wall of the aperture through which the spike passes, the lower end of the notch being inclined and positioned parallel

with and spaced apart from the inclined face of the rib when the spike is driven in place, as set forth.

In testimony whereof I hereunto affix my signature in presence of two witnesses.

H. E. HARRIS.
